UNITED STATES PATENT OFFICE.

RANSOM E. OLDS, OF DETROIT, MICHIGAN, ASSIGNOR TO OLDS MOTOR WORKS, OF DETROIT, MICHIGAN, A CORPORATION OF MICHIGAN.

VAPORIZING DEVICE FOR EXPLOSIVE-ENGINES.

SPECIFICATION forming part of Letters Patent No. 792,158, dated June 13, 1905.

Application filed October 18, 1901. Serial No. 79,084.

To all whom it may concern:

Be it known that I, RANSOM E. OLDS, a citizen of the United States, residing at Detroit, in the county of Wayne and State of Michigan, have invented certain new and useful Improvements in Vaporizing Devices for Explosive-Engines, of which the following is a specification, reference being had therein to the accompanying drawings.

10 The invention relates to new and useful improvements in vaporizing devices for explosive-engines, and particularly in the construction of the devices for making the gas and feeding the same to the engine in proper mixture, all as more fully hereinafter described, and particularly pointed out in the claims.

In the drawings, Figure 1 is a side elevation of a gas-engine, showing my improvement applied thereto. Fig. 2 is an enlarged perspective view showing the air and gas conduit, the controlling-valve, and the oil-inlet pipe. Fig. 3 is a longitudinal section therethrough. Fig. 4 is a cross-section of Fig. 3 on line α α . Fig. 5 is a diagram sectional elevation showing the oil-circulating pipes, the reservoir-pumps and engine, and the oil-feed-regulating valve and air and gas conduits.

A represents a gas-engine of any of the usual types, B being the crank-case thereof. C represents the conduit leading to the end of the cylinder for conveying the gas thereto, and D is the air-inlet pipe, which I have shown in this case provided with the perforated end E, the pipes E, D, and C forming a continuous pipe for the air and gas.

At the beginning of the gas-conduit C, I preferably form the vertically-narrowed passage α . (Shown in Fig. 3 and in dotted lines in Fig. 4.) This port is controlled by a valve, preferably a vertically-sliding gate-valve b , which I have shown as adapted to be actuated by a bell-crank c , to which is connected an actuating-rod d , by means of which the operator may open the valve, a spring e being provided for normally holding it in its closed position, as shown in Fig. 4. The valve b is cut away at the lower corners to form the normally open ports h upon opposite sides, so

that when the valve is closed these ports are still open at opposite sides of the port α . In 50 immediate adjacency to this narrowed port or throat is an oil-inlet pipe F, having its discharge at the top of the air-inlet pipe E. Below this oil-inlet is preferably arranged a well G, with the exit-port i at the bottom connecting into a return oil-pipe H'.

I preferably arrange a tapering foraminous carrier H for the stream of oil, which will pass from the inlet-pipe F to the exit-port i .

With the devices hereinafter described or other suitable devices a stream of oil is caused to pass through the oil-pipe F and descend across the air-inlet pipe E transversely, carried by the foraminous carrier H and any surplus passing out through the return-pipe H'. The valve b being in the position shown in Fig. 4, the movement of the piston will draw air through the pipe E and the port h , take up such vapors as will escape from the passing stream of oil on the carrier H, and enter the gas-pipe C and thence into the engine, where they will be ignited in the well-known manner. If it is desired to increase the strength of the charge, the operator draws on the rod d , lifting the valve b from its seat 75 slightly, thereby increasing the size of the air-port in a narrow passage-way arranged across and in close proximity to the stream of oil, which will produce a sort of jet effect, causing this narrow jet to cut off a part of the 80 oil in the carrier H and carry it, with the air, into the gas-pipe C. As the valve b is open more or less, the amount of oil carried by the air will be increased, and as the carrier H is tapering the wider the valve is opened the 85 greater amount of oil will be carried with the air. I find with the ordinary service on comparatively level roads the ports h , taking up the vaporization from the carrier H, give me a proper mixture, and that for heavier roads 90 or climbing hills or greater speed the valve b may be operated.

At the bottom of the well G, I arrange a vent-pipe I, which extends up a slight distance above the bottom of the well, so that 95 oil will not flow out of the same and so that

the suction of the engine will not draw with it the oil which may be in the well and maintaining atmospheric pressure in the pipe H'.

J is a suitable valve for controlling the oil-supply.

In the oil-supply pipe I preferably place a proper fitting, in this case shown as an elbow K, having on its under side a well L, the lower end of which is closed by a screw M. This well being located in close proximity to the valve J will catch any sediment or heavy particles there may be in the oil, and thus prevent the clogging of the valve which controls the oil-supply. This well may be emptied at any time by simply removing the screw end, when the oil and the sediment therein will run out, and the screw may then be replaced.

N is the oil-reservoir, from which leads the supply-pipe k, which discharges into the receptacle or chamber l, in this case shown as formed at the top of the stand-pipe m, which extends rather near the bottom of the reservoir N. The chamber l connects with the stand-pipe m by means of a restricted port n and also by means of an overflow-passage formed by the central pipe p. This overflow-pipe may be arranged in any other location; but by making it a central pipe I can pass through it the piston-rod q of a pump having the piston r, the stand-pipe m acting as the cylinder thereof. This pump is a hand-pump by means of which the operator may pump the oil by one or more operations into the chamber l, and from thence it will flow by gravity through the pipe F to the carrier H and operate in the manner described.

When the engine is started, a constant stream of oil is maintained through the pipe F by means of the diaphragm-pump O. This pump consists of a suitable casing, as shown in Fig. 5, with the diaphragm s stretched across the same, one side of the diaphragm being connected, by means of the pipe P, with the crank-casing B, so that the pulsations in the crank-case will cause the diaphragm to vibrate. The chamber on the other side of the diaphragm is connected by the pipe Q into the valve-casing R in the lower part of the reservoir N, this valve-casing having an inlet and outlet port controlled by check-valves in the usual manner in pumps, the inlet-port connecting into the reservoir and the outlet-port connected into the pipe k. This construction is fully shown in Fig. 5, and as it is the usual arrangement of check-valves for pumps I do not think it necessary to further describe the parts. The return-pipe H' leads to the bottom of the reservoir N.

The operation of these parts is as follows:

After the necessary oil for starting the engine is obtained by means of the hand-pump and the engine has started to run then the pulsations in the crank-case B operating a diaphragm s will pump a continuous stream of

oil into the chamber l, and from thence it will be fed through the pipe F across the air-inlet pipe in the carrier H, and any surplus passing into the well G will be carried backward to the receptacle through the return-pipe H'. When the engine is stopped, the oil in the chamber l will flow back into the receptacle through the ports n. By having the overflow-pipe in the chamber l any surplus oil that may be pumped by the diaphragm-pump will flow back into the reservoir, and a substantially uniform stream of oil will be fed by gravity from the receptacle through the pipe F, as the oil cannot extend above the height of the overflow-pipe p.

While I have shown the valve l beyond the oil-stream, and I consider this a much more desirable arrangement, it may be placed upon the other side of the oil-stream so long as the stream is arranged in close proximity to the narrow port a.

What I claim as my invention is—

1. In a gas-engine, the combination with an air-pipe, having an inlet adjacent its forward end, and an outlet, of means arranged intermediate said inlet and outlet for feeding a stream of oil transversely therethrough, and means adjacent the outlet of the pipe for varying the size of the air-passage therethrough to cause the air to cut off and carry with it only so much of the oil-stream as is proportionate to said air-passage.

2. In a gas-engine, the combination with an elongated air-pipe having an inlet adjacent its forward end, an outlet adjacent its rear end, and a gas-conduit at its rear end, of means adjacent said outlet end for feeding a stream of oil transversely therethrough, and a valve adjacent the gas-conduit and to the rear of said last-mentioned means for varying the size of the air-passage and causing the air to cut off only so much of the oil-stream as is proportionate to an air-passage.

3. In a gas-engine, the combination with an elongated air-pipe having an inlet adjacent its forward end and a gas-conduit at its opposite end, of means adjacent said opposite end for feeding a stream of oil transversely therethrough, and means within the gas-conduit, adjacent said last-mentioned means for varying the size of the air-passage and causing the passing air to cut off only so much of said oil-stream as is proportionate to said air-passage.

4. In a gas-engine, the combination of an air-inlet pipe, means for feeding a constant stream of oil transversely therethrough, a gate-valve in the air-pipe arranged in close proximity to the oil-stream, said valve normally having an opening, and means for enlarging the portage thereof.

5. In a gas-engine, the combination of an air-inlet pipe, means within the pipe for feeding a stream of oil transversely across the same,

- and means for exposing a varying length of the stream affected by the air-current, by varying the size of the air-outlet adjacent the oil-stream.
5. In a gas-engine, the combination of an air-inlet pipe, means for feeding a stream of oil transversely therethrough free from the sides, a valve for closing the air-pipe opposite the oil-stream, and having a normally open port adjacent its lower end beside the oil-stream, whereby only the vapor therefrom is picked up by the air, and means for enlarging the portage.
6. In a gas-engine, the combination with a longitudinally-extended air-pipe, of an oil-inlet intermediate its ends, a transverse conductor passing through the air-pipe in line with the oil-inlet, a well below the conductor extending below the air-passage, a return-pipe from said well, and an adjustable gate-valve adjacent the exit end of the air-pipe for causing the air to cut off an amount of oil proportionate to the oil-opening.
7. In a gas-engine, the combination with an air-pipe, of a conductor for directing a stream of oil transversely across the same, said conductor increasing in its oil-retaining capacity from one end thereof to the other.
8. In a gas-engine, the combination with an air-pipe, of an air-inlet pipe, of means for feeding transversely therethrough a constant stream of oil wider at the top, and means for varying the size of the air-inlet opening from below, whereby the area of the oil-stream exposed to the action of the air-current is so varied as the volume of air is increased, the ratio of oil is also increased more than the simple increase in length of the stream exposed to the action of the air-current.
9. The combination with an air-inlet pipe, of means for feeding a constant stream of oil transversely therethrough free from the sides, a valve for controlling the air-passage adjacent to the oil-stream, a normally open port in the valve beside the oil-stream,
10. In a gas-engine, the combination of an air-inlet pipe, means for feeding a stream of oil transversely therethrough free from the sides, a valve for closing the air-pipe opposite the oil-stream, and having a normally open port adjacent its lower end beside the oil-stream, whereby only the vapor therefrom is picked up by the air, and means for enlarging the portage.
11. In a gas-engine, the combination with an air-inlet pipe, of an oil-supply pipe communicating therewith, means extending in line with the supply - pipe and communicating therewith for conducting the oil transversely through the air-pipe, said means being tapered throughout its length, and means for varying the size of the air-passage adjacent the transverse oil-stream, for varying the amount of the stream to be affected by the air.
12. In a gas-engine, the combination with an air-inlet pipe, of a foraminous oil-conductor passing transversely therethrough, said conductor tapering from one end to the other, and a valve adjacent thereto.
13. In a gas-engine, the combination with an air - inlet pipe, of an oil - conductor passing transversely therethrough, said conductor being tapered throughout its length, and means adjacent the oil-conductor for varying the size of the air-passage whereby the varying area of the oil will be affected by the air.
14. In a gas-engine the combination with an air-inlet pipe, an oil-conductor passing transversely therethrough, and a valve in the air-pipe adjacent the conductor, said valve normally having an opening therethrough at its bottom.
15. In a gas-engine, the combination with an air - inlet pipe, of an oil - conductor passing transversely therethrough, said conductor being tapered, a valve in the air-pipe, said valve normally having an opening, and means for varying the portage thereof.

In testimony whereof I affix my signature in presence of two witnesses.
